(57) CLAIM

I claim the ornamental design for a food product, as shown and described.

DESCRIPTION

FIG. 1 is a top perspective view of a food product showing my new design;

FIG. 2 is a bottom perspective view thereof;

FIG. 3 is a rear elevation view thereof;

FIG. 4 is a left side elevation view thereof;

FIG. 5 is a top view thereof;

FIG. 6 is a right side elevation view thereof;

FIG. 7 is a bottom view thereof;

FIG. 8 is a front elevation view thereof; and,

FIG. 9 is a top perspective view thereof, where the food item is broken apart to show thickness.
